UNITED STATES PATENT OFFICE

2,616,133

CLOTHES RETAINER APPARATUS

Leo Peters, Evanston, Ill.

Application August 6, 1949, Serial No. 108,937

12 Claims. (Cl. 20—16)

1

This invention relates to clothes retainer apparatus. The apparatus is particularly useful when employed in connection with the exterior of a service door or building panel.

There has long been a need for an inexpensive and effective guard means which may be controlled by the housewife or a delivery man selectively for the safeguarding of clothes to be dry-cleaned or laundered in the period prior to the picking up of the clothes when the housewife is away from home and in the period when the clothes have been delivered and prior to the return of the housewife. A problem has existed in the provision of apparatus accomplishing the above purposes by the use of few and inexpensive parts and in the provision of parts which may be controlled by simple and inexpensive locking means.

I have heretofore suggested door guards which had clamping bars hinged to swing open with a movement outwardly from the door. When some of such clamping bars are completely open, they may stand at right angles to the door and extend outwardly as much as two and one-half feet. A problem is presented in that two doors are employed in many homes and buildings, and the space between such doors is usually no more than six inches. For example, screen doors are often used and in the northern part of the country, storm doors are employed. Under the circumstances, unless the delivery man and the housewife are very careful to keep the screen or storm door open while the clamping bar is extended, these doors may be pierced or damaged by the extended clamping bar. This is a difficult operation particularly if the bundle of clothes is heavy or the areaway in which the screen doors, etc. swing, is small and narrow.

There is a further problem presented with such swinging clamping bars in that children or adults may hang or lean upon the end of the hinge or supporting structure which is easily damaged. There has long been a need for a clamping bar which with a slight movement may be swung upwardly or downwardly within the space between the two doors while at the same time providing simple locking means which may be controlled by the delivery man through the use of an authorized key, or controlled by the housewife by a simple means such as opening or closing the door.

An object of the present invention is to overcome the above disadvantages and to satisfy the needs described. A further object is to provide in a clothes retainer apparatus, a pin bar hav-

ing at least one pin for supporting clothes and a clamping bar apertured to receive the pin and pivotally mounted upon the pin bar, means associated with the door jamb being provided for maintaining the clamping bar in confining relation when the door is closed while releasing it when the door is open, the locking means controlled by the delivery man being operable independently of the position of the door. A further object is to provide a jamb for the outer end of the clamping bar formed by a grooved section of the door jamb so that the clamping bar is automatically released when the door is opened and held in locked position when the door is closed. A further object is to provide a clamping bar mounted upon pins and being adapted to pivot upon the pins at either end thereof in the locking and unlocking movements of the clamping bar relative to the pins and door jamb. Yet another object is to provide a hasp which serves the dual purpose of a jamb for a clamping bar and a locking means for itself. A still further object is to provide a single unit locking means which permits a clamping bar to be swung open with precisely the same movement and in the same manner whether it is automatically unlocked when the housewife opens the door, or when it is unlocked by a delivery man with a key. Yet another object is to provide a unique locking structure for releasably securing a bag upon a service door or building panel through the use of bars movably mounted with respect to each other and independently operable by a housewife through the opening or closing of the door and by a delivery man through the unlocking and locking of a key-controlled lock. Other specific objects and advantages will appear as the specification proceeds.

The invention is illustrated, in preferred embodiments, by the accompanying drawings, in which—

Figure 1 is a perspective view of a door equipped with clothes retainer apparatus embodying my invention; Fig. 2, a broken perspective view of the bar retainer parts shown in separated relation; Fig. 3, a transverse sectional view, the section being taken as indicated at line 3—3 of Fig. 1; Fig. 4, an enlarged, broken sectional view of a portion of the structure shown in Fig. 3; Fig. 5, a broken perspective view showing the unlocking of the clamping bar when the key-controlled lock is released by the delivery man; Fig. 6, a view similar to Fig. 1, but showing a modified form of clothes retainer apparatus; Fig. 7, a perspective view of the bar and locking parts, the various

parts being shown in separated relation; Fig. 8, a transverse sectional view of the modified structure shown in Fig. 6; Fig. 9, an enlarged broken sectional view showing a portion of the structure illustrated in Fig. 8; Fig. 10, an enlarged broken sectional view showing the hinged end of the clamping bar structure illustrated in Fig. 8; Fig. 11, a perspective view of a door equipped with a second modified form of clothes retainer apparatus; Fig. 12, a broken perspective view of the bar and associate parts, the bar and other parts being shown in separated relation; Fig. 13, a transverse sectional view of the structure shown in Fig. 11; and Fig. 14, a broken transverse sectional view similar to Fig. 13, but with the door 10 swung partially inwardly.

In the illustration given in Figures 1 to 5 inclusive, the door 10 is shown provided with glass window panels 11. It will be understood that the apparatus is applicable to a solid door, as well as to a paneled door. The apparatus disclosed, however, is particularly useful in connection with paneled doors in that the structure may be suspended across the panels while still providing a sturdy support for pins or projections across the paneled portions of the door, and also permitting unimpaired light and vision through the door panels if the latter are made of transparent glass.

In the illustration given, pin bar 12 is secured to the door 10 at opposite ends of the panel 11 by means of screws 13 or other suitable means. The bar 12 is provided with forwardly-extending projections or pins 14 which are in spaced relation. A central pin 14 may be used for supporting a clothes hanger or any other support for clothes. If desired, a bag 15 provided at its open top with spaced apertures may be secured upon the pins 14 and clamped in closed position by the use of a clamping bar 16. A satisfactory type of bag is described in detail in my co-pending application, Serial No. 99,486, filed June 16, 1949, for Clothes Container and Guard.

The clamping bar 16 may be of any suitable form or construction. In the illustration given, the bar 16 is provided with openings 17 for receiving the pins 14 when the bars are brought into clamping relation as illustrated in Fig. 3. The clamping bar may be movably supported upon the pin bar 12 by any suitable means. I have found that particularly good results are obtained where the bar 16 is pivotally mounted at either end upon a fixed pivot slidably engaging a recess in the bar. As shown more clearly in Figs. 2 and 3, the pin bar 12 is provided at its inner end near the hinge 18 of door 10 with a pivot stud 19. The stud 19 is provided near its outer end with a transverse opening 20 through which is extended the U-bolt of a key-controlled lock 21. It will be understood that a combination lock or other lock which may be operated only by an authorized person may be employed.

The pin bar 12 is also provided at its end near the free end of the door with a pivot stud 22 which also extends through an opening in the clamping bar 16. The openings in the clamping bar 16 for receiving the pins 14 and the pivot studs 19 and 22 are preferably sufficiently large to allow play by the bars so as to facilitate the unlocking and the locking of the clamping bar relative to the pin bar.

The clamping bar 16 is provided at its end adjacent the free end of the door with a locking extension 23 adapted to engage a recess 24 in the door jamb 25, as shown more clearly in Figs. 3, 4 and 5.

Operation

In the operation of the structure shown in Figs. 1 to 5 inclusive, the clothes may be suspended in a bag upon the pins 14 or in any other type of clothes hanger or support and the clamping bar may then be swung to confining relation about the bag and over the pins 14, the door being swung inwardly to release the bar 16 for this movement. It will be understood that the bar 16 may swing upon pivot stud 19 with the lock 21 engaging the same, as illustrated in Fig. 3. The door may then be closed as illustrated in Fig. 3 and upon the locking of the door, the clamping bar 16 is maintained in locked position.

When the delivery man arrives, he will unlock the lock 21 and release the inner end of bar 16. The bar may then be swung about pivot stud 22 as illustrated in Figs. 1 and 5 so as to release the locking projection 23 from engagement with the recess 24 of the door jamb 25. The delivery man may remove the bag containing the goods to be cleaned or, if he is delivering cleaned clothes, he will secure the bag upon the pins 14 and swing the clamping bar 16 back to clamping position with the pivot stud 22 extended through the corresponding opening in the bar 16. The lock 21 will then be replaced and locked to maintain the parts again in the jamb-confining relation illustrated in Figs. 3 and 4.

In the modification illustrated in Figs. 6 to 10 inclusive, the clamping bar 26 is connected by a universal pivot to the pin bar 27. The universal pivot structure may be of any suitable type. In the illustration given, the clamping bar 26 is cut away at one end as indicated at 28 in Fig. 7 and a vertical pivot sleeve 29 is provided for raising a vertical pivot pin 30 which extends through the spaced flanges of clamping bar 26. The vertical sleeve 29 is provided with an integral pin 31 pivotally secured to the pin bar 27, thus permitting the clamping bar 26 to swing outwardly in a plane horizontal with the plane of pin bar 27 to enable the bar 26 to clear the pins 32 and then after the pins are cleared, the bar 26 may be swung upwardly or downwardly upon the pivot pin portion 31.

The clamping bar 26 is preferably provided with spaced side flanges 33 between which is adapted to be extended a locking hasp 34. The hasp 34 is pivotally mounted at 35 upon the retainer plate 36 and is apertured at 31 to receive a fixed U-bolt 38. An ordinary key-controlled or combination lock 39 may be employed to engage the U-bolt 38, as shown in Fig. 9, to secure the hasp 34 in a locked position illustrated in Fig. 9.

In the operation of the structure shown in Figs. 6 to 10 inclusive, the door 10a may be swung inwardly to release the clamping bar 26 from engagement with hasp 34 and the housewife may place a bag of clothes upon the pins 32. The door may then be swung closed and locked. The clothes are now securely held within the bag until the delivery man arrives and unlocks lock 39. The hasp may then be swung to the position indicated by the dotted lines in Fig. 9 and the clamping bar 26 is thus released for outwardly-swinging movement, as illustrated in Fig. 8. The bag may then be removed or a new bag containing freshly cleaned clothes may be placed upon the pins 32. The clamping bar is then swung into closed position and the hasp 34 restored to the locked position shown in Fig. 9.

In the modification shown in Figs. 11 to 14 inclusive, the door 10b is provided with a pin bar 40. The bar 40 is provided with the pins or

projections 41 adapted to be passed through aligned openings in the top of an open-ended bag or employed in any other manner for supporting clothes. A segmental clamping bar 42 is supported upon pin bar 40 in the manner illustrated best in Figs. 11, 13 and 14. The segmental bar 42 consists of a long segment 43 which is equipped with slots 44 adapted to receive the pins 41 for slidable movement. At the end of the door 10b adjacently hinged thereof, the bar 42 is provided with a hook 45 which extends through a slot 46 in the segment 43 of the clamping bar 42.

The other segment of the clamping bar 42 is a relatively short segment 47 and it is provided with a slot 48 adapted to receive the shank of a headed-confining bolt 49. Thus the segment 47 is slidably secured for a limited sliding movement on the pin bar 40. The segment 47 is provided with an outwardly-turned flange 50 which is apertured at 51 to receive the neck 52 of an outwardly-turned flange 53 with which the long segment 43 is provided. As shown more clearly in Figs. 13 and 14, the flange 53 is extended through the opening 51 of flange 50 and lies against the outer face of flange 50. The flanges 50 and 53 are provided with aligned holes adapted to receive the U-bolt 54 of a lock 55. These holes are sufficiently large to allow a pivoting movement of the bar segment 53 relative to the bar segment 47, as shown more clearly in Fig. 14 so that the bar 53 will clear the pins 41 and permit ready access to the bag or other clothes-supporting means carried by pins 41.

In the operation of the structure shown in Figs. 11 to 14 inclusive, the two bar segments 43 and 47 will ordinarily be locked together by the bottom of lock 55, as shown in Fig. 13. When the housewife desires to place a bag of clothes upon the pins 41, she may swing the door 10b inwardly as illustrated in Fig. 14. This permits the clamping bar 42 to slide toward the free end of the door clearing the hook 45 and the segment 53 to be swung outwardly so as to clear the pins 41 and the entire bar 42 may be swung downwardly, as indicated in Fig. 11 upon the pivot 49. When the bag or other means carrying the clothes is placed on pins 41, the bar 42 may be swung upwardly and then the segment 53 may be swung inwardly to receive the pins 41. The entire bar 42 may then be slid inwardly towards the hinged end of the door to bring the bar 42 under hook 45 as illustrated in Fig. 13. In this position, the other end of the bar 42 (segment 47) will abut the door jamb 25b and will prevent the bar 42 from being moved out of the latched position shown.

When the delivery man arrives, he may unlock and remove the lock 55. This releases the bar segment 43 and it may be slid toward the free end of the door to disengage it from the hook 45. The bar segment 43 may then be swung to the position shown in Fig. 14 to clear the pins and then moved downwardly or upwardly as desired upon the pivot 49. This permits the delivery man to remove the bag of clothes or place a bag containing finished clothes upon the pins 41. Locking of the structure is effected by again sliding the bar segment 43 toward the hinged end of the door and placing the lock 55 back in position as illustrated in Fig. 13.

While I have shown a bar equipped with pins for holding a bag, it will be understood that the bar may be equipped with flanges or other means for receiving and holding the mouth portion of the bag.

In all of the foregoing description with respect to operation, it will be understood that the various locking and unlocking operations may be carried out in any desired sequence. I prefer to employ a bag for the confining of clothes upon the bars but it will be understood that any other suitable means for retaining clothes thereon may be employed.

While in the foregoing specification I have set forth specific structures in considerable detail for the purpose of illustrating embodiments of my invention, it will be understood that such details may be varied widely by those skilled in the art without departing from the spirit of my invention.

I claim:

1. In a container supporting apparatus of the character set forth, a pin bar secured to the outer surface of a door mounted in a door frame, said door frame being provided at a point adjacent the free end of the door with a locking recess, spaced projections carried by said pin bar, a clamping bar having openings adapted to receive said projections but adapted to pivot upon the end projections thereof, said bar being provided at one end with a large extension adapted to engage the recess of said frame, and locking means for confining the other end of said bar upon the projection at the other end of said clamping bar.
2. In a container supporting apparatus of the character set forth, a pin bar secured to the outer surface of a door mounted in a door frame, said door frame being provided at a point adjacent the free end of the door with a locking recess, spaced projections carried by said pin bar, a clamping bar having openings adapted to receive said projections but adapted to pivot upon the end projection thereof, said bar being provided at one end with a large extension adapted to engage the recess of said frame, and a key-controlled lock for confining the other end of said bar upon the projection at the other end of said clamping bar.
3. In a clothes retainer structure of the character set forth, a bar adapted to be secured to the outside of a door mounted within a frame, projections carried by said door, a second bar mounted upon said first-mentioned bar for movement outwardly therefrom and laterally thereof, and means carried by said door and door frame for releasably confining said second bar in confining relation about said projections.
4. In a clothes retainer apparatus adapted to be secured upon the outside of a door mounted in a door frame, a bar carried by said door and equipped with outwardly-extending projections, a segmental bar slidably mounted upon said first-mentioned bar, said bar segments being slideable with respect to each other and provided with aligned flanges, locking means for releasably securing said flanges together, and a hook member carried by said first-mentioned bar and engageable with said second-mentioned bar when said bars are moved laterally toward the hinged end of the door.
5. In a clothes retainer apparatus adapted to be secured to a door mounted in a door frame, a projection bar secured to the door and equipped with outwardly-extending projections, a segmental bar slidably secured to said first-mentioned bar and provided with slots to receive said projections, a hook fixed to said first-mentioned bar and adapted to engage said second-mentioned bar to lock the same when said second-mentioned bar is slid towards the hinged end of the door, and a key-controlled locking means for releas-

ably securing said bar segments together, said second-mentioned bar when engaged by said hook having its outer end abutting the door frame to prevent release of said bar as long as said door remains in closed position but permitting sliding of the second-mentioned bar to release the same from said hook when said door is opened.

6. In combination with a door mounted for swinging movement within a door frame, a bar secured to the outside of said door and equipped with spaced pins, a clamping bar provided with recesses receiving said pins and mounted for movement toward and away from said pin bar, and means pivotally mounting said clamping bar upon said first-mentioned bar, whereby at least one end of said clamping bar engages said door frame and is confined thereby against separation from said first-mentioned bar, said clamping bar being swingable to a position away from said first-mentioned bar when said door is open.

7. In combination with a door mounted for swinging movement in a door frame, a pin bar secured to the outside of the door and provided with an outwardly-extending pin, a clamping bar pivotally mounted upon said pin bar and provided with a recess receiving said pin, means on said door frame confining said clamping bar against movement away from said pin bar when the door is in closed position, said clamping bar being released from said last-mentioned means when the door is open to permit said clamping bar to be swung away from said pin bar, and lock-controlled means permitting separation of said clamping bar from said pin bar independently of the position of said door.

8. In combination with a door mounted for swinging movement in a door frame, a pin bar secured to the outside of said door and carrying at least one pin, and a clamping bar pivotally secured upon said pin bar and provided with a recess receiving said pin, said door frame and the end of said clamping bar being interlocked

to prevent separation of the clamping bar from the pin bar when the door is in closed position, said clamping bar being released for pivotal movement when said door is opened.

5 9. The structure of claim 8, in which the door frame is equipped with a movable abutment engageable with the end of the clamp frame.

10 10. The structure of claim 8, in which the frame is equipped with a hinged member swingable into a position for confining the end of the clamping bar against said pin bar, and key-controlled lock means for securing said abutment in said confining position.

15 11. In combination with a door mounted for swinging movement in a door frame, a pin bar secured on the door frame and equipped with a plurality of pins extending outwardly therefrom, a clamping bar movably mounted for movement toward and away from said pin bar and provided with apertures receiving said pins, and means carried by said door frame and engageable with one end of said clamping bar for securing said clamping bar in locked position against said pin bar, said clamping bar being released for movement away from said pin bar when said door is opened to move said clamping bar away from said securing means.

20 12. The structure of claim 11, in which the clamping bar is formed in two parts connected 25 together by key-controlled locking means.

30 LEO PETERS.
